UNITED STATES PATENT OFFICE

2,369,581

LIFTER ROOF

Donald E. Larson, Chicago, Ill., assignor to Chicago Bridge & Iron Company, a corporation of Illinois

Application November 28, 1941, Serial No. 420,879

5 Claims. (Cl. 48—176)

This invention relates to improvements in lifter roofs and more especially such a device in connection with a tank, shell or container adapted for the storage of gases, or volatile liquids.

Among the features of my invention is the provision of guiding means for the roof causing it to rotate as it rises and falls in much the same manner as a lifter roof with spiral guide rails. The means I employ, however, is much cheaper and simpler in construction and operation than the employment of guide rails and has other advantages that will be pointed out hereinafter.

In general my invention comprises a series of slanting rocker arms with their lower ends pivoted to the tank and their upper ends to the roof so that it is more level as it moves upwardly and downwardly. The rocker arms must rotate in unison and therefore the roof cannot tip even though loads or forces are applied to it at one or more points.

One advantage of my invention is that the entire guiding arrangement is completely outside the tank where its operation may be observed and where any necessary adjustments or repairs can be made without taking the tank out of service.

Another advantage is that the action of the rocker arm guides is not materially affected by ice or snow. They have such great leverage that any resistance caused by an accumulation of ice or snow on the flexible joints at the ends of the arms is readily overcome.

Another feature of the invention is that the rocker arms operate with a minimum of friction and offer almost no resistance to the movement of the roof.

It is to be noted also that the rocker arms can be easily installed so that erection costs are reduced as compared with other systems.

Other features and advantages of my invention will appear more fully as I proceed with my specification.

In that form of device embodying the features of my invention shown in the accompanying drawings, Fig. 1 is a view in side elevation; Fig. 2 is a top plan view with a portion of the roof broken away; Fig. 3 is a vertical sectional view taken as indicated by the line 3, 3 of Fig. 4; and Fig. 4 is a view on an enlarged scale showing the action of the guiding arrangement.

As shown in the drawings, 10 indicates a cylindrical tank or shell with the bottom 11, and 12 a vertically movable roof therefor.

13 indicates a trough around the top of the shell which may be either on the outside as here shown or on the inside (not shown). The trough

is filled with a sealing liquid 14 which, for example, may be water in warm climates or brine in colder ones. The roof 12 is provided at its periphery with a depending flange 12a having its lower edge immersed in the liquid 14, thus providing a liquid seal between the shell and the roof.

The outer edge of the roof 12 is provided with a peripheral extension 12b carrying an outer depending flange 12c. The members 12b and 12c form a weather-hood or protecting means for the trough 13 and prevent the entrance of undesirable foreign matter into said trough.

For the purpose of guiding the roof in its vertical movements and preventing it from tipping, I provide a plurality of rocker arms 15 having their lower ends pivoted at 16 to the brackets 17 on the shell 10 and their upper ends pivoted to the members 18 carried by the angle-iron 19 on the lower edge of the depending flange 12c of the weatherhood.

The upper ends of the pivot arms 15 are provided with rollers 20 engaging the outer surface of the trough 13 to center the roof and assist in holding it in proper position.

As the roof rises and falls the arms 15 rock, as shown in Fig. 4, in unison and thus prevent the roof from tipping. It will be seen that the rocking of the arms also gives the roof a rotary motion in its vertical movements.

The upper ends of the arms 15 are pivoted to the members 18 on the pivot pins 18a. 16a indicates the pivot pins for the lower ends of the arms. There is enough lost motion in both the upper and lower pivots to permit the slight twisting of the arms 15 caused by the rotary motion of the roof in its vertical movements.

Although I have shown a liquid seal between the tank and the roof it is obvious that this seal may be made in other forms. For example, a wiper type seal could be used. In each case it will be seen that the seal remains effective as the roof moves vertically. Such a seal therefore, in general, may be referred to as a flexible seal.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

What I claim as new, and desire to secure by Letters Patent, is:

1. A mechanism for holding the movable cover of a stationary vertical cylindrical type fluid storage container to its normal path of motion with respect to the container as the volume of stored fluid changes, comprising a plurality of at least three spaced links of substantial length distributed around said cover a substantial distance from its center, each link having one end pivoted to the cover and the other end pivoted to a fixed part of the apparatus, each link being mounted at an angle of about 90° to a radius of said cover, and all of said links being mounted at the same angle with respect to a horizontal plane as determined in one direction around the cover and in the same relationship with respect to said cover, whereby said cover is caused to rotate with respect to said container when the cover moves up and down.

10

20

2. A mechanism as set forth in claim 1, in which a flexible seal is provided between the container and the cover.

3. A mechanism as set forth in claim 1, in which a liquid seal is provided between the container and the cover.

4. A mechanism as set forth in claim 1, in which the links are provided with anti-friction members bearing against the outside of the container.

5. A mechanism as set forth in claim 1, in which a liquid seal is provided between the container and the cover, including a trough on the container, and means are provided on the cover protecting said trough against entry of foreign matter thereto.

DONALD E. LARSON.
